Patented Feb. 22, 1921.

Inventor:

Carl E. Tillman.

By: - Alfred, Rose & Shuster

Atty's:

UNITED STATES PATENT OFFICE.

CARL E. TILLMAN, OF CHICAGO, ILLINOIS.

DESIGN FOR A CONTAINER FOR CIGARS.

57,173.

Specification for Design.

Patented Feb. 22, 1921.

Application filed June 12, 1920. Serial No. 388,651. Term of patent 7 years.

To all whom it may concern:

Be it known that I, CARL E. TILLMAN, a citizen of the United States, residing at Chicago, in the county of Cook and State of Illinois, have invented a new, original, and ornamental Design for a Container for Cigars, of which the following is a specification, reference being had to the accompanying drawing, forming a part thereof, in which is shown a front view in elevation of the container, showing my new design.

I claim:

The ornamental design for a container for cigars, as shown.

CARL E. TILLMAN.

Witnesses:

SARAH E. HARVEY,
LURLINE BULLWINKEL.
